INNER BOXCAR DOOR

Corry L. Brown, Kansas City, Mo.

Application February 23, 1951, Serial No. 212,389

11 Claims. (Cl. 20—29)

1

This invention relates to inner closures for box car doors to permit loading of a box car with bulk material such as grain or other commodities such as sack flour which must be kept out of contact with the sliding outer door to permit movement of the outer door without tearing of the sacks.

The principal objects of the invention are to provide an inner door for railway box cars that is of simple construction and which becomes a permanent part of the box car; to provide an inner door that effectively closes the door opening to prevent leaking of grain through the door opening; to provide an inner door structure which cooperates with the inner walls of the box car to form a substantially smooth interior surface; to provide a permanently attached inner door that does not interfere with operation of the sliding outer door or interfere with use of the car for purposes that do not require an inner door; and to provide an inner door structure that is securely locked in closed position and cannot become disengaged under shocks resulting from braking or bumping the car incidental to switching or train operation.

Other objects of the invention are to provide an inner door structure having substantially the same height as the open doorway except for an inspection and loading opening; to provide an inner door structure which in itself securely retains and supports the contents of a car and thereby permits the use of a lighter outer door structure; and to provide an inner door that is readily operated by one man.

It is also an object of the invention to provide an inner door structure which permits entrance and exit of air into and out of the car to prevent condensation by maintaining substantially uniform inner and outer temperatures.

In accomplishing these and other objects of the invention as hereinafter pointed out, I have provided improved inner door structure, the preferred form of which is illustrated in the accompanying drawings wherein:

Fig. 1 is a perspective view of a portion of a box car equipped with inner doors constructed in accordance with the present invention and showing the outer door in open position to better illustrate the inner door sections, one of which is illustrated in closed position and the other being moved from its storage position into closed position.

Fig. 2 is a vertical section through the side wall of the car showing the inner door in closed position, the section being taken on the line 2—2 of Fig. 3.

2

Fig. 3 is a side elevational view of the box car, showing the outer door in open position and the inner door sections in closed and latched position, a portion of the side wall of the car being broken away to better illustrate mounting links for the inner door sections.

Fig. 4 is a horizontal section on the line 4—4 of Fig. 3.

Fig. 5 is a perspective view from the interior of the car and showing one of the door sections in closed position and the other in retracted or stored position.

Fig. 6 is a vertical section through the side of the car on the line 6—6 of Fig. 5, particularly illustrating the pocket in which the door section is enclosed when in retracted position.

Referring more in detail to the drawings:

1 designates a standard railway box car having a side wall 2 provided with a door opening 3 and which is normally closed by a sliding door 4 movable on upper and lower rails 5 and 6 that are attached to the side of the box car. The door 4 and rails 5 and 6 may be of standard construction in that they specifically form no part of the present invention. However, because of the present invention, the door may be of lighter weight and constructed of lighter materials.

When a box car of this character is used for holding bulk commodities such as grain it is necessary to equip the car with an inner closure which usually consists of transverse boards nailed to the inner side of the door frame and which are lined with paper to cover any knots or cracks between the boards. Such inner closures are also necessary where the car is loaded with commodities such as sacks of flour that must be kept out of contact with or lodgement against the sliding outer door 4 which would prevent sliding opening of the door or result in damage to the goods when the outer door is open. Application and removal of the boards often results in damaging of the door posts of the car to which the boards are nailed. Such inner doors are also of short life because of splintering and splitting of the boards from which they are constructed.

The present invention overcomes these difficulties by providing inner doors of sufficiently simple and inexpensive construction so that each box car may be provided with a permanently attached inner door that becomes a part of the car and is housed in an out-of-way position when not required.

In carrying out the present invention, the inner side 7 of the car wall 2 is provided at the respective sides of the door opening with shields

8 and 9, each including a substantially rectangular panel 10 that is spaced from the inner side 7 and extends from the car floor 11 to a point above the head jamb 12 of the door for providing a pocket 13 therebetween. The lower edge 14 of each panel closely engages the floor 11 so as to prevent leakage of grain and similar bulk material thereunder into the pockets 13. The upper edges 15 of the panel sections terminate in laterally extending webs 16 forming closures for the upper ends of the pockets and which have flanges 17 for attaching the panels to the inner face of the side wall by fastening devices such as screws or the like 18. The rearmost edge 19 of each panel with respect to the door opening carries a sloping wing 20 that closes that side of each pocket and which is secured to the inner face of the side wall of the car by flanges 21 similar to the flanges 17. The web 16 preferably terminates short of the wings 20 so as to provide openings 22 that cooperate with openings 23 in the floor of the car to provide vertical ventilation through the pockets for a purpose later described. The wings 20, sloping to the inner face of the car wall, provide smooth inner surfaces so as to prevent damage to commodities such as sacks of flour and the like that may be stacked against the side walls of the car and panel 10. The edges 24, which are disposed at the sides of the door opening, are unattached and substantially register with the inner faces of the side jambs or door posts 25. The edges 24 have retractively turned flanges 26 that are spaced from the inner face of the panels to provide vertical grooves 27 therebetween. The panels, being of metal, may have the outer faces covered with an insulating material 28 such as plywood or the like to better conform with the character of the inner face of the side walls of the car.

The inner door 29 or closure comprises a pair of abutting door sections 30 and 31 having a combined width sufficient to cover the width of the door openings between the door posts 25. The door sections are of a height to extend from the floor to a point above the lower edge of the head jamb 12 and are adapted to be stored when not in use within the respective pockets 13. The door sections may be formed of sheet metal or other suitable material and have hook-like flanges 32 extending vertically of the outer side edges thereof and which are adapted to inter-engage the flanges 26 when the door sections are in position to close the door opening as best shown in Fig. 4, the flanges 32 being spaced from the inner face of the door sections to provide vertical grooves 33 for receiving the flanges 26 when the hook-like flanges 32 are engaged in the grooves 27 of the panels 10 so as to provide tight joints therebetween. The forward edge of one of the door sections, for example the door section 30, is provided with a relatively thick vertical style 34 to accommodate a vertical groove 35 in the edge thereof for receiving the abutting edge 36 of the other door section 31 when the doors are in closed position.

When the door sections are closed, the lower edges 37 thereof seat within a groove 38 that is formed by inner and outer sill plates 39 and 40 that are attached to the top of the car door sill 41 as best shown in Figs. 2 and 4. Thus, the lower edges of the door sections are retained in stable position against shifting weight of the load and provide seals to prevent grain and similar bulk materials from leaking into the space 42 that is provided between the inner and outer

doors. The outer sill plate is co-extensive with the door opening. However, the inner sill plate has extensions 43 at the ends thereof which overlap the lower end edges of the panels, as best shown in Fig. 5. The adjacent edges of the sill plates have notches at substantially the mid-points thereof, as indicated at 44 and 44', to accommodate the style of the door section 30 therein when the doors are in closed position. The upper corners at the abutting edges of the door sections are provided with notches 45 and 46 to form an inspection or fill opening 47 when the doors are closed. The upper edge of each door section is also provided with a hook-like flange 48 that is adapted to engage a similar hook-like flange 49 on a plate 50 that is attached to the inner face of the car wall above the head jamb of the door opening as best shown in Fig. 5 and which cooperates with extensions 51 of the panels to form ways 52 in which the upper ends of the door sections are supported when in closed position. The extensions include depending flange portions 53 registering with the under-face of the door jamb and have web portions 54 that terminate in attaching flanges 55 similar to the attaching flanges 17 previously described.

The door sections are each supported on pairs of parallel hinge links 56-57 and 58-59. The links have lower ends that are pivotally mounted on studs 60 projecting inwardly within the pockets 13 from the side wall 2, the links being retained in proper spaced position by sleeves 61 that are mounted on the studs, as shown in Figs. 2 and 3.

The upper ends of the links are similarly pivoted to the door sections on studs 62 as best shown in Fig. 3. It is thus obvious that the door sections are held in vertical position and are adapted to swing in a vertical plane out of and into the pockets when moving to and from closing relation with the door opening.

Since space must be provided for swinging of the links, grain and similar commodities may tend to lodge on the sill and flow into the space between the side wall of the car and the doors. This is prevented by providing the inner-most of the lower links with guards 63 that have a yoke-shaped end 64 straddling the respective links and have eyes 65 mounted on pivot pins 66 that are carried by the links. The guards are of sufficient width and length to close the space between the side wall and the door sections and to depend into contact with the floor of the car. The guards also have offsets 67 to accommodate the pivotal connection for the forwardly positioned links when the sections are closed. When the door sections are closed, the guards are locked in position between the foremost links and lugs 68 that project from the lower outer corners of the door sections.

The door sections are substantially balanced by coil springs 69 having one end connected with studs 70 projecting from the outer sides of the doors and their opposite ends connected with studs 71 that project inwardly from the side wall of the car. The doors are latched in closed position by a hook-shaped catch 72 that is pivotally mounted on one door section as indicated at 73 and which has a hooked end 74 that is adapted to engage over a keeper 75 on the other door section. The latch is supported from swinging movement on the pivot 73 when in unlatched position by means of a keeper 76 which forms a support for the latch when it is swung into retracted position.

The outer sides of the door sections may be provided with lugs 77 to form handles by which the doors may be pushed into the pockets or withdrawn therefrom. The doors may also be provided with lugs 78 by which they may be raised to start the pivotal movement thereof as when opening the door to discharge grain or other bulk commodities. The lower ends of the door may be clamped together by a latch lever 79 that is pivotally mounted on a pin 80 carried by the door section 30 and which latch lever has a laterally extending pin 81 adapted to engage over a cam lug 82 on the other door section 31. It is obvious that the lever 79 and the cam lug 82 operate to draw the doors tightly together. To further assist in holding the doors in closed position, the lever 79 may be provided with a detent portion 83 that engages in a recess 84 formed in the adjacent sill plate and door sill of the car, as best shown in Fig. 3. The lever may be locked in latched position by a keeper 85 that is pivotally mounted on a pin 86 carried by the door section 31, the keeper having a recess 87 adapted to receive the end of the latch lever when the keeper is in position shown in Fig. 3.

In operating the door constructed and assembled as described and assuming that the door sections are in retracted position the operator engages the lugs 77 and pulls on the door sections to cause swinging movement thereof in an upward direction toward the door opening. As the links move past their dead center position, the door sections begin to swing forwardly and downwardly to seat the lower edges thereof into engagement with the groove between the sill plates. After both door sections are in closed position, they are secured together by the latch 72 and clamping lever 79. When the door sections are closed, the hook flanges on the side and upper edges inter-engage the corresponding hook flanges that are rigidly carried by the pocket panels so that with the sill and style grooves a grain tight seal is provided about the entire margins thereof. The car may then be filled with grain by inserting the fill spout (not shown) into the opening 47. After the car is filled, the outer door may be closed and sealed as in conventional manner. The contents of the car may be readily inspected by opening the outer door to give access to the contents through the opening 47.

During shipment the interior of the car is kept at substantially the same temperature as the external temperature by air circulation through the vent openings in the bottoms of the door pockets, openings at the front edges of the pockets 13, space between the inner and outer doors and through the fill openings into the car. Cross ventilation is also provided in like manner from the vent openings at one side of the car to the other side. The vent openings also provide for discharge of material that might pass into the door pockets.

When the car is to be unloaded the keeper 85 is released and the clamping lever 79 swung to retracted position. The catch lever 72 is also released and a lifting force is applied to the lugs 78 to lift first one door section and then the other to cause the sections to move into retracted position within the pockets. As the doors lift, grain in the car begins to spill under the lower edges thereof as the edges of the door sections clear the sill plates. Grain is prevented from flowing into the space between the side wall of the car and the door sections by the pivoted guards 16. As the pressure of the grain is released, the doors are

easily swung into retracted position with aid of the coil springs 69. When the car is loaded with sacks of flour or packaged goods, the inner door sections are shifted into the door pockets and the sacks of flour are trucked through the open door and stacked in desired manner. When the car is filled, the inner door sections are closed as above described to protect the load from contact with the exterior doors and to permit free closing and opening thereof.

From the foregoing it is obvious that I have provided a simple inner door construction for box cars and the like which is easily installed and which forms a permanent part of the car. It is also obvious that the inner door sections form a positive seal around the peripheral edges thereof to prevent leaking out of bulk materials such as grain and to assure that the door sections remain in tight clamped-together position when they close the car door opening. It is also obvious that when the doors are retracted into pockets they are completely out of the way so that the car equipped therewith may be used for any purpose where inner doors are not required.

What I claim and desire to secure by Letters Patent is:

1. In a box car having a side wall provided with a door opening, an inner door closing said opening at the inner side of said wall including a pair of door sections adapted to cover the opening on the inner side of said wall, links having pivotal connection with the door sections and the inner side of said wall for supporting the sections for movement in a vertical plane parallel with the inner face of said wall from said position closing the opening to retracted positions at sides of the door opening, shields having portions spaced from the inner side of said wall and provided with flange portions coextensive with upper edges opposite from the door opening to form pockets to receive the door sections therein when the door sections are in open position, said door sections being spaced from the inner side of said wall to accommodate movement of the links, and means closing said space below the lowermost of said links.

2. In a box car having a side wall provided with a door opening, an inner door closing said opening at the inner side of said wall including a pair of door sections adapted to cover the opening on the inner side of said wall, links having pivotal connection with the door sections and the inner side of said wall for supporting the sections for movement in a vertical plane parallel with the inner face of said wall from said position closing the opening to retracted positions at sides of the door opening, pocket forming means at sides of the door opening to house said door sections, and guards pivotally suspended from a link at each side of the door opening and extending to the lower portion of the door opening to close entrance to the lower portion of the space in which the links operate in said pocket forming means.

3. In a box car having a side wall provided with a door opening, an inner door closing said opening at the inner side of said wall including a pair of door sections adapted to cover the opening, links having pivotal connection with the door sections and with the inner side of said wall for supporting the sections for movement in a vertical plane parallel with the inner face of said wall from said position closing the opening to retracted position at sides of the door opening, shields spaced from the inner side of said wall at the

respective sides of the door opening and coextensive with the height of the door and forming pockets having entrances registering with side edges of the door sections for passing the door sections into said pockets, hook like flanges on said shields in substantial registry with sides of the door opening and facing inwardly of said pockets, and complementary flanges standing along sides of the door sections in facing relation with the flanges on said shields for forming seals between the door sections and shields when the door sections are in closed position.

4. In a box car having a side wall provided with a door opening, an inner door closing said opening at the inner side of said wall including a pair of door sections adapted to cover the opening, links having pivotal connection with the door sections and with the inner side of said wall for supporting the sections for movement in a vertical plane parallel with the inner face of said wall from said position closing the opening to retracted position at sides of the door opening, shields spaced from the inner side of said wall at the respective sides of the door opening and coextensive with the height of the door and forming pockets having entrances registering with side edges of the door sections for passing the door sections into said pockets, hook like flanges on said shields in substantial registry with sides of the door opening and facing inwardly of said pockets, complementary flanges standing along sides of the door sections in facing relation with the flanges on said shields for forming seals between the door sections and shields when the door sections are in closed position, downwardly facing hook like flanges extending along upper edges of the door sections, and a complementary hook like flange extending transversely across the upper portion of the door opening to engage the downwardly facing hook like flanges and form a seal with the wall of the box car at the upper portions of the door sections.

5. In a box car having a side wall provided with a door opening, an inner door closing said opening at the inner side of said wall including a pair of door sections adapted to cover the opening, links having pivotal connection with the door sections and with the inner side of said wall for supporting the sections for movement in a vertical plane parallel with the inner face of said wall from said position closing the opening to retracted position at sides of the door opening, shields spaced from the inner side of said wall at the respective sides of the door opening and coextensive with the height of the door and forming pockets having entrances registering with side edges of the door sections for passing the door sections into said pockets, hook like flanges on said shields in substantial registry with sides of the door opening and facing inwardly of said pockets, complementary flanges standing along sides of the door sections in facing relation with the flanges on said shields for forming seals between the door sections and shields when the door sections are in closed position, downwardly facing hook like flanges extending along upper edges of the door sections, and a complementary hook like flange extending transversely across the upper portion of the door opening to engage the downwardly facing hook like flanges and form a seal with the wall of the box car at the upper portions of the door sections, the inner edge of one of said door sections having a groove for receiving the corresponding edge of the other section and form a seal between said door sections.

6. In a box car having a side wall provided

with a door opening, an inner door closing said opening at the inner side of said wall including a pair of door sections adapted to cover the opening, links having pivotal connection with the door sections and with the inner side of said wall for supporting the sections for movement in a vertical plane parallel with the inner face of said wall from said position closing the opening to retracted position at sides of the door opening, shields spaced from the inner side of said wall at the respective sides of the door opening and coextensive with the height of the door and forming pockets having entrances registering with side edges of the door sections for passing the door sections into said pockets, hook like flanges on said shields in substantial registry with sides of the door opening and facing inwardly of said pockets, complementary flanges standing along sides of the door sections in facing relation with the flanges on said shields for forming seals between the door sections and shields when the door sections are in closed position, downwardly facing hook like flanges extending along upper edges of the door sections, a complementary hook like flange extending transversely across the upper portion of the door opening to engage the downwardly facing hook like flanges and form a seal with the wall of the box car at the upper portions of the door sections, the inner edge of one of said door sections having a groove for receiving the corresponding edge of the other section and form a seal between said door sections, and interengaging cam means on the respective door sections for securing the door sections together in maintaining said seals.

7. In a box car having a side wall provided with a door opening, a sliding door closing said opening at the outer side of said wall, an inner door closing said opening at the inner side of said wall including a pair of door sections adapted to cover the opening, links having pivotal connection with the door and the inner side of said wall for supporting the sections for movement in a vertical plane parallel with the inner face of said wall from said position closing the opening to retracted positions at sides of the door opening, said inner and outer doors being spaced apart to provide an air circulating space, and pocket forming means at sides of the door opening and cooperating with the side wall to provide entrances for the doors to house said door sections and having connection with said air circulating space through said entrances, said pockets having air vents in bottoms thereof and in connection with said pockets, and the inner door sections having an opening connecting the interior of said circulating space with the interior of the car to provide substantial equalization of temperature between the interior and exterior of the box car.

8. In a box car having a side wall provided with a door opening, a sliding outer door closing said opening at the outer side of said wall, an inner door closing said opening at the inner side of said wall including a pair of door sections adapted to cover the opening, links having pivotal connection with the door sections and the inner side of said wall for supporting the sections for movement in a vertical plane parallel with the inner face of said wall from said position closing the opening to retracted positions at sides of the door opening, said door sections having an inspection opening, pocket forming means having entrances at sides of the door opening for passing the door sections into the pocket forming means when the door sections are moved

to retracted position, said entrances having connection with space between the inner and outer doors, and said car having vent openings in bottoms of said pockets for admitting air into said space for outlet into the car through the inspection opening.

9. In a box car having a side wall provided with a door opening, an inner door closing said opening at the inner side of said wall including a pair of door sections adapted to cover the opening, links having pivotal connection with the door sections and the inner side of said wall for supporting the sections for movement in a vertical plane parallel with the inner face of said wall from said position closing the opening to retracted positions at sides of the door opening, pocket forming means having entrances at sides of the door opening for passing the door sections into the pocket forming means when the door sections are moved to retracted position, and guards carried by said links for closing said entrances adjacent the lower portion of the door opening.

10. In a box car having a side wall provided with a door opening, an inner door closing said opening at the inner side of said wall including a pair of door sections adapted to cover the opening, links having pivotal connection with the door and the inner side of said wall for supporting the sections for movement in a vertical plane parallel with the inner face of said wall from said position closing the opening to retracted positions at sides of the door opening, pocket forming means having entrances at sides of the door opening for passing the door sections into the pocket forming means when the door sections are moved to retracted position, guards carried by selected links in closing relation with said entrances adjacent the lower portion of the door opening, means on the door sections en- 40

gaging a part on said guards to retain the guards in said entrance closing position when the door sections are closing the door opening, and hook-like flanges on sides of said sections and the entrances of the pocket forming means and adapted to inter-engage when the door sections are in closing position to prevent leakage between the pocket forming means and the door sections.

11. In a box car having a side wall provided with a door opening, an inner door closing said opening at the inner side of said wall including a pair of door sections adapted to cover the opening, means for supporting the door sections for movement in a vertical plane parallel with the inner face of said wall from said position closing the opening to retracted positions at sides of the door opening, pocket forming means having entrances at sides of the door opening for passing the door sections into the pocket forming means when the door sections are moved to retracted position, guards for closing said entrances adjacent the lower portion of the door opening, and means on the door sections engaging a part of said guards to retain the guards in said entrance closing position when the door sections are closing the door opening.
